UNITED STATES PATENT OFFICE.

JOHN F. JANKOWSKI, OF ST. LOUIS, MISSOURI, ASSIGNOR TO DAZEY CHURN & MANUFACTURING CO., OF ST. LOUIS, MISSOURI, A CORPORATION OF MISSOURI.

CAN OPENER.

Application filed May 26, 1926. Serial No. 111,728.

My invention relates to improvements in can-openers and has for its purpose to provide a can-opening hand tool adapted to cut the head of the can in alinement with the inner face of the wall of the can, and thus permit a solid can content to be dumped without breakage.

This object is attained by a curved pointed blade so diverging from a curved guard as 10 to force the cutting edge of the blade into contact with a point on the inner face of the lid directly in alinement with the inner face of the wall of the can.

The guard is preferably of slightly greater 15 width and length than the blade, to protect the blade from accidental injury. The guard is also apertured to provide ready access to the adjacent face of the blade for cleaning the blade.

20 The inner faces of the blade and guard are so contoured, and diverge from each other at such an angle, as to pinch or squeeze the upper edge of the can between them during the entire cutting operation, thus keeping the 25 blade pinched against the inner face of the wall of the can during the entire cutting operation, as well as holding the blade in the proper position to cut the head cleanly from the can so that no fragments of the head 30 when cut will remain overhanging the interior of the can.

Drawings.

In the drawings—

35 Fig. 1 is a side elevation of a tool embodying my invention.

Fig. 2 is a sectional fragmental view of a 40 can-head showing a front elevation of the tool in its initial position after being thrust through the can-head.

Fig. 3 is a similar view showing the tool in cutting position.

Fig. 4 is a top view of the can-head and tool in the cutting position shown in Fig. 3.

Description.

As shown in the drawings, the tool of my invention embraces a handle A wherein the shank 10 of the shank-and-guard piece B is 50 mounted. The piece B is so curved at 18 that the blade-seat 11 and blade 12 will be offset and out of alinement with the handle A. Upon the blade-seat 11 the blade 12 is mounted, and forward of the line of mounting the blade 12 and guard 13 so diverge

from each other as to pinch or squeeze the top edge 14 of the can C being opened between them, as shown in Figs. 2 and 3.

The guard 13 has the outwardly-turned terminal lip 13^a, and is apertured at 15 to 60 permit the adjacent face of the blade 12 to be readily cleaned through the aperture.

The terminal lip 13^a extends beyond the blade-point 16, and the sides of the guard 13 extend beyond the sides of the blade 12, as 65 shown in Fig. 1, so as to protect the cutting edges of the blade 12 from injury, due to the accidental dropping of the tool upon a hard surface, or like causes.

Mode of operation.

The blade-point 16 is thrust through the can-head 17 at any point conveniently near the periphery of said can-head 17 (see Fig. 2). A continued downward thrust will bring 75 the cutting edge of the blade 12 into engagement with the top of the flange 19, thus removing the can-head 17 in exact vertical alinement with the inner face of the wall of the can C. (See Figs. 3 and 4.) The handle 80 A is then pressed rearwardly and downwardly, forcing the blade 12 upwardly with a forward cut, then raised, and the blade 12 forced forwardly and downwardly to its next cutting position, and by successive strokes of the 85 blade 12 the entire can-head 17 is cleanly cut from the can C, leaving no fragments overhanging the interior of the can C.

It will be observed that the blade 12 is so 90 mounted as to cut the top of the flange 19 formed around the periphery of the can-head 17, and leaving the outer rim of that flange 19 in place after the cutting operation is completed. Thus, at all times during the cutting operation the blade 12 and 95 guard 13 have two thicknesses of the sheet metal (of which the can C and can-head 17) are made between them; so that, due to the divergence of the blade 12 and guard 13, the tool is fulcrumed in the bite or pinch 100 formed by this divergence and the resulting contact and pressure upon the inner face of the wall of the can C, and the outer face of the flange 19; and there is no fulcruming of the tool upon the top edge of the can C 105 (see Figs. 2 and 3). This fulcruming I have determined by actual test to result in the clean and entire removal of the head 17, and to prevent the accidental slipping of the tool; the tool being at all times held in place 110

by the opposed pressure of the blade 12 and guard 13. The degree of that pressure is properly such as will keep the tool in position upon the can whenever the hand of the 5 operator is released from the tool. To make clear this biting or gripping engagement of the tool with the can I have indicated as 20 in Figs. 2 and 3 the open space existing above the flange 19 and between the blade 10 12 and guard 13 during the cutting operation.

Variations of form of the tool thus described can be effected without departure from my actual invention as defined by the 15 appended claims.

I claim:

1. A can opener comprising a handle and a shank, a guard on the shank, a blade carried by the shank adjacent to and coextensive with the guard throughout the major portion of the length of the guard, the guard being appreciably spaced from the blade throughout the major portion of its length to receive the wall of the can therebetween to 20 properly position the opener and prevent lateral tilting thereof, and said guard and blade throughout the minor portions of their length being convergent to their points of 25

connection with the shank thereby to form a sharp acute angle adapted to pinch the 30 bead of the can to form a fulcrum and to maintain the blade against the wall of the can.

2. A can opener comprising a handle and a shank, a guard formed on the shank, a blade carried by the shank adjacent to and coextensive with the guard throughout a major portion of the length of the guard and the free ends of the guard and blade being bent outwardly from each other, the guard being appreciably spaced from the blade throughout a major portion of its length to receive the wall of the can therebetween to properly position the opener and prevent lateral tilting thereof, and said guard and blade throughout the minor portions of their length being convergent to their points of connection with the shank thereby to form a sharp acute angle adapted at all times to pinch the bead of a can to 40 45 form a fulcrum and to constantly maintain the blade against the wall of the can. 50

In testimony whereof I have hereunto affixed my signature.

JOHN F. JANKOWSKI.
